MOUNTING FOR ELECTRIC SWITCHES

Winton G. Harlow, Springfield, Pa., assignor to
 General Electric Company, a corporation of
 New York

Application August 3, 1938, Serial No. 222,872

8 Claims. (Cl. 200—162)

My invention relates to improvements in mountings for electric switches and particularly disconnecting switches which are used to establish a conductive connection between two terminals which although substantially parallel may not be in alignment.

Disconnecting switches particularly such as the hinged flat blade type with tongue or jaw contact require a nicely of register between the moving contacts in order to secure the maximum current carrying capacity. Occasions arise where it is difficult and costly to obtain the necessary register. For example, with some types of circuit breakers, disconnecting switches commonly called subcell disconnecting switches are arranged in a chamber or cell below the circuit breaker. In such cases the disconnecting switch has one contact mounted on the circuit breaker terminal stud which projects through a wall of the sub-cell. The other contact is mounted on a terminal which projects through the opposite wall of the cell. Obviously if the two terminals even though parallel are not in alignment, the desired register of disconnecting switch contacts will not occur. While the terminal on the circuit breaker and the terminal in the sub-cell can readily be made substantially parallel, it is at best a tedious and costly procedure to align them. An object of my invention is to provide an improved switch mounting which eliminates such procedure.

In accordance with my invention, I eliminate such costly fitting and adjusting by a relatively inexpensive adjustable mounting for the switch contacts whereby the necessary adjustment to secure the desired register of contacts is easily and simply obtained for any misalignment of terminals to be expected with reasonably good workmanship. This and other objects of my invention will appear in more detail hereinafter.

My invention will be better understood when considered in connection with the accompanying drawing, and its scope will be pointed out in the appended claims.

In the accompanying drawing, Fig. 1 illustrates in perspective a disconnecting switch provided with mountings embodying my invention; Fig. 2 is a vertical elevation partly in section of the embodiment of my invention shown in Fig. 1 as applied to a sub-cell disconnecting switch; and Fig. 3 is a detail illustrating the adjustable feature of my switch mounting.

Referring now to the several figures of the drawing, two terminals 1 and 2, which may be respectively an outgoing terminal and the end

of a circuit breaker stud, have between them a conductive connection which can be broken at will although not ordinarily while current is flowing. As shown, the conductive connection is a disconnecting switch comprising one or more sets of relatively movable cooperating contacts 3 and 4. The contacts 3 may comprise two parallel flat bars pivotally mounted at 5 on a hinge tongue 6 suitably secured to or forming a part of a support 7. As shown the stationary contact 4 is of the tongue type and may be secured to or form a part of a support 8. Either one or both of the supports 7 and 8 may be adjustably secured to the terminals 1 and 2 in accordance with my invention as will hereinafter appear. Suitable means such as spring washers 9 may be used at the hinge and terminal ends of the blades 3 to provide the desired contact pressure.

The terminal 1 may be mounted in an insulator 10 which projects through an opening in the cell wall 11 and is suitably secured thereto by a flanged member 12 and bolts 13. Terminal 2, which may be the end of a circuit breaker stud, extends through an insulator 10 which projects through an opening in the cell wall 14 and is suitably secured thereto by a flanged member 12 and bolts 13. In order to hold the disconnecting switch in the closed position in the cell, it is provided with a latching means such as a latch 15 pivotally mounted at 16 on a projection 17 of the blades 3. Also mounted on the blade projection 17 is an eye or ring member 18 which, when engaged by a switch-operating hook and moved in a clockwise direction, first rotates at its pivot point 19 on the projection 17 to release the latch 15 and, upon further movement, actuates the blades 3 to the open position where they may be retained by a hook 20 pivotally depending from the support 7 to engage a projection such as a pin 21 on the blades 3.

Obviously, even in the run of ordinary workmanship, it is too much to expect that the terminals 1 and 2 will be in such alignment that the blades 3 will make good enough contact at the hinge and jaw ends to provide the desired current carrying capacity if the supports 7 and 8 are merely attached to the terminals without any allowance for offset thereof. In order to take care of this probability of lack of alignment without the necessity of changing bolt holes, moving the circuit breaker or other expedients, I provide an adjustable mounting whereby either one or both of the supports 7 and 8 may very readily be moved in any direction at right angles to the associated terminal. As shown, this mounting

is an eccentric type. It may take the form of a nut 22 which screws on to the threaded terminal and comprises a cylindrical portion or surface 23 which is eccentric to the terminal itself. The 5 supports 7 and 8 are provided with cylindrical apertures which engage the cylindrical surface 23 of the nut 22 so that by relative movement of the nut on the support any desired offset or displacement of the support relatively to the terminal, 10 within the range of adjustment of the eccentric, may be provided.

In order to prevent any relative movement of the parts once this offset is adjusted to compensate for the misalignment of the terminals, 15 the nut 22 and the support or at least the portion thereof which engages the nut 22 may both be slit as at 24 and 25 and the support provided with a draw bolt 26 the tightening of which maintains the parts in the desired position. While 20 I have shown the nut 22 as provided with a hexagonal head 27, it will be obvious that any other suitable arrangement may be provided for turning the nut relatively to the terminal so as to secure the desired movement. While the eccentric 25 adjustment feature may be provided for only one terminal, a greater leeway in adjustment may be obtained if both terminals are similarly provided with an adjustment feature embodying my invention so as to permit the necessary adjustment without any alteration in or movement of the 30 circuit breaker, insulators or cell walls.

While I have shown and described my invention in considerable detail, I do not desire to be limited to the exact arrangements shown, but seek to 35 cover in the appended claims all those modifications that fall within the true spirit and scope of my invention.

What I claim as new and desire to secure by Letters Patent of the United States, is:

40 1. In a mounting for a disconnecting switch comprising a movable contact and a cooperating stationary contact for establishing a conductive connection between two spaced terminals which may be misaligned and one of which supports one 45 of said contacts, means for adjustably positioning the other of said contacts on the other of said terminals to correct for lack of alignment thereof whereby to insure the correct registering action of said contacts comprising an eccentric mounting 50 for supporting said other switch contact on said other terminal.

2. In a mounting for a disconnecting switch comprising relatively movable cooperating contacts for establishing a conductive connection between two spaced terminals which may be misaligned and one of which supports one of said contacts, means for adjustably supporting the other of said contacts on the other of said terminals comprising an eccentric nut engaging 55 said terminal and having an outer cylindrical surface and a support for said other contact having a cylindrical aperture for engaging the cylindrical surface of said nut.

3. In a mounting for a disconnecting switch 60 comprising relatively movable cooperating contacts for establishing a conductive connection between two spaced terminals which may be misaligned and one of which supports one of said contacts, means for adjustably supporting the other of said contacts on the other of said terminals comprising an eccentric nut engaging said

terminal and having an outer cylindrical surface and a support for said other contact having a cylindrical aperture for engaging the cylindrical surface of said nut, and means for preventing relative movement of the support, the nut, and 5 other terminal.

4. In a mounting for a disconnecting switch comprising a hinged flat blade and a cooperating flat stationary contact for establishing a conductive connection between two spaced terminals which may be misaligned, means for adjustably supporting the disconnecting switch blade on one 10 of said terminals comprising an eccentric nut engaging said one of said terminals and having an outer cylindrical surface, a support for the hinge 15 of said blade having a cylindrical aperture for engaging the cylindrical surface of said nut, and means for preventing relative movement of the support, the nut, and the terminal.

5. In a mounting for a disconnecting switch 20 comprising a hinged flat blade and a cooperating flat stationary contact for establishing a conductive connection between two spaced terminals which may be misaligned, means for adjustably supporting the disconnecting switch blade on one 25 of said terminals comprising an eccentric nut engaging said terminal and having an outer cylindrical surface, and a support for the hinge of said blade having a cylindrical aperture for engaging the cylindrical surface of said nut. 30

6. In a mounting for a hinged blade and co-operating stationary contact disconnecting switch for establishing a conductive connection between two spaced terminals which may be misaligned, means for adjustably supporting the disconnecting switch blade on one of said terminals comprising an eccentric member engaging one of the terminals and a member concentric with and engaging said eccentric member and constituting a support for the disconnecting switch blade, and 40 means for adjustably supporting the stationary contact on the other of said terminals also comprising an eccentric member engaging said other terminal and a member concentric with an engaging said eccentric member and constituting a 45 support for the stationary contact.

7. In a mounting for a disconnecting switch comprising relatively movable cooperating contacts for establishing a conductive connection between two spaced terminals which may be misaligned, means for adjustably positioning the contacts of the switch on said terminals to correct for lack of alignment thereof whereby to insure the correct registering action of said contacts comprising an eccentric mounting on one terminal for supporting one contact thereon and an eccentric mounting on the other terminal for supporting the other contact thereon. 55

8. In a mounting for a disconnecting switch comprising relatively movable cooperating contacts for establishing a conductive connection between two spaced terminals which may be misaligned and one of which supports one of said contacts, means for adjustably supporting the other of said contacts on the other of said terminals comprising an eccentric member engaging said other terminal and a member concentric with and engaging said first member and constituting a support for said other contact. 60
